[57] CLAIM

The ornamental design for a hockey helmet, as shown and described.

DESCRIPTION

FIG. 1 is a left elevational view of the hockey helmet of the present invention, the right side view of the helmet is symmetrical to the view shown in FIG. 1;

FIG. 2 is a front elevational view of the hockey helmet of FIG. 1;

FIG. 3 is a back elevational view of the hockey helmet of FIG. 1;

FIG. 4 is a top elevational view of the hockey helmet of FIG. 1; and,

FIG. 5 is a bottom elevational view of the hockey helmet of FIG. 1.

The broken line showing of the interior surfaces of the hockey helmet are for illustrative purposes only and forms no part of the claimed design.
